T. GORE.

CABLE.

APPLICATION FILED JUNE 2, 1921.

1,419,560.

Patented June 13, 1922.

Inventor:

Thomas Gore
By his Attorney
Frederick Beekman

UNITED STATES PATENT OFFICE.

THOMAS GORE, OF BROOKLYN, NEW YORK.

CABLE.

1,419,560.

Specification of Letters Patent. Patented June 13, 1922.

Application filed June 2, 1921. Serial No. 474,408.

To all whom it may concern:

Be it known that I, THOMAS GORE, a citizen of the United States, and a resident of the borough of Brooklyn, in the city of New York, county of Kings, and State of New York, have invented certain new and useful Improvements in Cables, of which the following is a specification.

This invention relates to a cable to be used for drilling and also as a mooring line or hawser and has for its main feature and object the production of an increased cushioning effect. This is particularly, though not exclusively, of value in drilling cables, such as that shown in Patent No. 1,071,734 of September 2, 1913, which shows a "cracker" of fibrous material surrounding twisted wire.

In the accompanying drawings the invention is disclosed in a concrete and preferred form in which—

Figure 1 is a side elevation of a length of cable embodying the invention: and

Figure 2 is a cross-sectional view on the plane of line 2—2 of Figure 1.

The cable is composed of a plurality of ropes 2 twisted together and each rope is composed of a plurality of strands 3. Either

Lang lay or regular lay may be used. Each strand is composed of a plurality of wires 4 twisted together and served around these twisted wires as a group are one or more layers of fibrous material such as a plurality of manila yarns 5. If desired, a core 6 may be provided within each rope and another core 7 may be provided between the several ropes and within the cable.

In Figure 1 the wires at one end of the cable are shown naked and with the fibrous covering tapering off in a manner similar to what is shown in Patent No. 1,071,734 in case it is desired to use the construction as a "cracker" in a drilling cable.

I claim:

A cable comprising: a plurality of ropes 45 twisted together, each rope consisting of a plurality of strands, and each strand consisting of a plurality of twisted wires served with a plurality of yarns, said yarns producing a cushioning effect not only between 50 the twisted strands of each rope but also between the twisted ropes of the cable.

Signed at Brooklyn, in the county of Kings and State of New York, this 28 day of May, 1921.

THOMAS GORE.
